UNITED STATES PATENT OFFICE

WILLIAM G. HERMSMEYER, OF FORT WORTH, TEXAS

HEAT REDUCING STRUCTURE FOR EXPLOSIVE ENGINES

Application filed May 29, 1929, Serial No. 366,851. Renewed March 30, 1932.

This invention relates to improvements in internal combustion engines.

The main object is to provide cooperating means for reducing the heat absorption of the cylinder walls and exhaust valves.

A further object is to provide means for centering the explosive force of the fuel charges more directly upon the central portions of the pistons, thereby increasing the power of work handling capacity of the explosion and concurrently reducing the exposure of the cylinder walls to the excessive heat of the explosions.

A further object is to provide means for reducing the exposure of the exhaust valve to the excessive heat of the exhaust gases, thereby minimizing the accumulation of carbon deposits thereon.

The foregoing and other objects, together with means whereby the same may be carried into effect, will best be understood from the following description of one possible embodiment of the invention, taken in connection with the accompanying drawings

25 wherein

Figure 1 is a vertical section through the upper portion of an internal combustion engine of the L-head type, showing my improvements embodied therein;

30 Figure 2 is a plan view of the directing ring removed from the engine.

Referring now more particularly to the drawings, the reference numeral 1 denotes an engine block of the L-head type having a plurality of cylinders, one of which is indicated at 2, and the pistons, as indicated at 3. The usual inlet and exhaust valves, as indicated at 4 and 5, are provided for each cylinder, the said piston and valves being here shown 40 as in the exhaust position. The foregoing elements are of conventional form and no invention is claimed therefor.

In carrying out the invention, I provide for each cylinder 2 a beveled combustion directing or centering ring 6, the outer diameter of the main portion of which corresponds to the inner diameter of the cylinder 2, the said rings each having a surrounding lip 7 adapted to fit in annular seats 8 formed 50 around the upper margin of the cylinders

as shown, to suspend the said rings within the cylinders. The inner, inwardly and downwardly sloping or beveled shoulder 9 is provided on each of the rings 6 for a purpose to be described. A cylinder head 10 carrying the usual spark plugs (not shown) is mounted over the cylinders 2 upon the block 1 in any suitable manner, and serves to hold the said combustion directing or centering rings 6 in place in the cylinders, as clearly shown in the drawings. Over each cylinder 2 a concaved, eccentric combustion recess 11 is chambered out of the underside of the said head 10; the said recess being cast off center towards the valves 4 and 5 and port 14, and over each individual inlet and exhaust valve 4 and 5 a separate valve receiving pocket 12 is formed in the head beside the said recess 11. The recess 11 and pockets 12 of each cylinder are of course spaced from those of the adjacent cylinder and are air-tight to prevent loss of compression and power in the engine. Each of the said valve pockets 12 is somewhat deeper than the companion combustion recess 11, thus forming a valve protecting shoulder 13 and the relatively restricted throat or port or passageway 14 connecting the said recess and valve pocket as shown.

In operation the combustible mixture is fed to the engine in the usual manner and enters the pockets 12 through the inlet valves 4 and flows into the combustion chambers through the ports 14. The eccentric disposition of the cupped or concaved combustion recesses 11, together with the sloping shoulders 9 of the rings 6, cause the violent agitation and through intermixing of the said combustible mixture when the mixture is drawn into the combustion chambers and facilitates the complete burning of the 50 said mixture. When the mixture is ignited, the inward and downward slope of the shoulders 9 of the rings 6 directs the full force of the explosions upon the central portions of the pistons 3, thus directing the heat away 55 from the cylinder walls. Thus the cylinder walls are prevented from becoming excessively heated. As shown in Figure 1, the exhaust valves 5, when raised, enter the valve pockets 12 and will be shielded from the 60

superheated exhaust gases by the shoulders 13 and the curved surfaces of the recesses 11, which will cooperate to deflect the exhaust gases downwardly through the ports 14, below the said valves, and thus protect the valves from the said gases when they are expelled from the cylinders on the exhaust strokes of the engine, thus avoiding the superheating and burning of the said valves and the formation of carbon thereon. Thus the said explosion centering rings 6 and the deflecting shoulders 13, together with the peculiar off center formation of the recesses 11, all cooperate to relieve the exhaust valves and cylinder walls from an excess of heat. So far as the intake valves 4 are concerned, it is true they still remain in the path of the exhaust gases, but this is considered rather as an advantage, as on the immediately succeeding intake strokes, the inflowing fuel becomes preheated as it passes into the combustion chambers, whereby instantaneous explosions are facilitated.

The inclination of the shoulders 9 in the combustion rings 6 and the diameter thereof will vary according to the bore and stroke and the speed of the engine upon which they are used as well as according to the type of fuel used by that engine.

It will be noted from Figure 1 that when the pistons 3 are at the extremity of their upward movement as shown, a small annular clearance space 15 will remain between the tops of the said pistons and the lower faces of the combustion rings 6, thus providing for carbon accumulations and metal expansion. The combustible mixture in these spaces 15 will be the last to burn and this provides a cooling effect and reduces detonation in the cylinder.

While I have herein set forth a certain preferred embodiment of my invention, it is understood that I may vary from the same in minor details, not departing from the spirit of the invention and within the scope of the appended claims. For instance, instead of the explosion centering rings 6 and shoulders 9 being formed circular, the same might be formed hexagonal at their inner margins or to any other desired configuration, without departing from the essence of my invention as defined in the claims.

I claim:

1. In an explosion engine cylinder having an annular seat formed around the inner margin of the cylinder bore at the combustion chamber end thereof, an explosion centering ring mounted in this end of the cylinder, the said ring being beveled inwardly to facilitate its function and having a surrounding lip adapted to fit in the said annular seat of the cylinder margin.

2. In an explosive engine, a cylinder having an annular seat formed around the inner margin of the cylinder bore at the combus-

tion chamber end thereof, an explosion centering ring mounted in this end of the cylinder, the said ring being beveled inwardly to facilitate its function and having a surrounding lip adapted to fit in the said annular seat of the cylinder, and a piston in the said cylinder, the travel of the piston being limited at its approach to the said explosion centering ring to leave a small annular cooling and clearance space between the piston and ring.

In testimony whereof I affix my signature.

WILLIAM G. HERMSMEYER.
